UNITED STATES PATENT OFFICE.

JAMES A. FULWILER, OF LEXINGTON, ILLINOIS.

RAG-JOINING KNIFE.

SPECIFICATION forming part of Letters Patent No. 288,991, dated November 27, 1883.

Application filed March 30, 1883. (No model.)

To all whom it may concern:

Be it known that I, JAMES ALVIN FULWILER, of Lexington, in the county of McLean and State of Illinois, have invented a new and Improved Rag-Joining Knife, of which the following is a full, clear, and exact description.

The object of my invention is to provide an improved rag-joining knife by which the ends 10 of rags used in making carpets, matting, &c., may be looped and joined with greater facility than by sewing them together.

The invention consists in a knife the blade 15 of which is sharpened at one edge, and provided with an inclined notch passing toward the point of the knife from the blunt back, for engaging the rags for drawing one through the other in forming the loop or joint, the inclined notch or slot being specially arranged with 20 relation to the sharp point and edge of the knife to join the rags firmly and smoothly and leave but short ends, thus avoiding waste of the rags and giving a much smoother finish to the face of the carpets woven from rags than 25 is possible when long ends are left loose at the joinings of the rags, all as hereinafter fully described and claimed.

Reference is to be had to the accompanying drawings, forming part of this specification, in 30 which similar letters of reference indicate corresponding parts in all the figures.

Figure 1 is a side elevation of my improved rag-joining knife; Fig. 2, a back edge elevation thereof; Fig. 3, an elevation of the sharp edge of the knife, and Fig. 4 a cross-section thereof on line $\alpha\alpha$, Fig. 1.

The drawings represent my improved knife as formed of a bar, a , of steel, turned or looped at one end, as at b , to form a handle, and for 40 a convenient means of hanging the knife to a pin or nail when out of use.

The blade c of the knife is forged or shaped for most of its length to the cross-sectional form of Fig. 4, with a blunt back, d , and a sharp 45 edge, e , which edge e extends to the extreme end f of the spear-shaped head g , the back of which, at h , is blunt, also as shown in Fig. 2, while the spear-head g is tapered gradually at both sides to a point.

50 I cut an inclined slot or groove, i , in the head h , at the back, and about parallel with the back edge, h , of the head, thus forming a hook,

k , which projects beyond the back d of the body of the knife, to more easily catch the rags in looping them together, the direction of the 55 slot i being more nearly in line with the length of the knife-blade than is usual with knives of this class, thus insuring a better hold of the rags in drawing them through the incisions made by the spear-head and sharp edge of the 60 knife.

In using the knife for joining rags, they are laid one over the other with the ends even, and the spear-head g is passed through both rags near the ends, and the outer rag drawn 65 partly and its joint end wholly through the incision of the inner rag by catching the outer rag at one side of the incision made therein in the slot i , and drawing it by the hook k , after which the end of the outer rag is carried over 70 the inner one by the hook-head, and said outer rag again caught in the knife-head slot and drawn by the hook through the incision made in the rag next its end, and carrying the end of the inner rag with it, when the hook k may 75 be disengaged entirely and the outer rag fully drawn through the incision next its end, thus forming the loop, which may be drawn tightly 80 by pulling upon both rags at each side of the loop, forming the joint quickly, smoothly, and 85 perfectly, leaving very short ends of the rags outside the joint and avoiding waste.

This improved knife may also be used for sewing heavy goods—such as bags and belt- 85 ing—by piercing the same by the spear-head and drawing the thread or cord back and forth through the goods by the hook; and the device will be useful, also, for securing tags to goods in a substantially like manner, and it may be used also as a button-hole cutter, and for drawing 90 corks by the hook, and for other useful purposes.

It will be understood that the loop b may be dispensed with and the knife-blade set in a wood or other suitable handle, as may be most 95 desirable or convenient.

Having thus described my invention, what I claim as new, and desire to secure by Letters Patent, is—

1. A rag-joining knife having blade c , sharp- 100 ened at one edge, e , and with a spear-head, g , having a slot, i , about parallel with the blunt back h of the head, substantially as shown and described.

2. A rag-joining knife having blade *c*, having one sharp edge, *e*, a spear-head, *g*, with slot *i*, about parallel with the blunt back edge, *h*, of the head, and forming a hook, *k*, which extends at its end beyond the blunt back *d* of the body *c* of the knife, substantially as shown and described.

3. A rag-joining knife having blade *c*, with spear-head *g*, and slot *i*, forming a hook, *k*,

which projects beyond the back of the blade, to said blade being sharp at edge *e* and blunt at edges *d h*, and the head *g* being tapered to a point at the sides, substantially as shown and described.

JAMES ALVIN FULWILER.
